DESIGN FOR WRAPPING PAPER

John W. Elder, Chicago, Ill.

Application April 5, 1944, Serial No. 113,139

Term of patent 14 years

(Cl. D59—2)

To all whom it may concern:

Be it known that I, John W. Elder, a citizen of the United States, residing at Chicago, county of Cook, and State of Illinois, have invented a new, original, and ornamental Design for Wrapping Paper, of which the following is a specification, reference being had to the accompanying drawing forming a part thereof.

The figure is a plan view of a piece of wrapping paper embodying my new design.

I claim:

The ornamental design for wrapping paper, as shown.

JOHN W. ELDER.
